CLAIM

The ornamental design for a kerosene heater, as shown and described.

DESCRIPTION

FIG. 1 is a front, top and right side perspective view of a kerosene heater showing our new design;
FIG. 2 is a front elevational view thereof;
FIG. 3 is a right side elevational view thereof;
FIG. 4 is a top plan view thereof;
FIG. 5 is a rear elevational view thereof;
FIG. 6 is a left side elevational view thereof;
FIG. 7 is a bottom plan view thereof; and
FIG. 8 is a front, top and right side perspective view of an alternate embodiment thereof, the only difference residing in the appearance of the cylindrical core element.
